UNITED STATES PATENT OFFICE.

EARL C. AKERS, OF DETROIT, MICHIGAN.

DOOR CHECK.

Application filed October 22, 1920, Serial No. 418,874. Renewed May 10, 1922. Serial No. 559,397.

To all whom it may concern:

Be it known that I, EARL C. AKERS, a citizen of the United States of America, residing at Detroit, in the county of Wayne 5 and State of Michigan, have invented certain new and useful Improvements in Door Checks, of which the following is a specification, reference being had therein to the accompanying drawings.

This invention relates to a device for checking or retarding the closing movement of doors and the like which are swung to closed position by springs or other automatic means, the tension or power of which are increased 10 by the swinging of the door to open position. All known checking or retarding devices are arranged to come into action shortly before the door comes to closed position so that the power of the closing device will not be 15 lessened thereby and the inertia of the swinging movement of the door may assist in the closing movement. The resistance of the checking means must be sufficient to prevent slamming when the door is opened to 20 its full extent and the closing means is put under maximum tension thereby to exert its full force in swinging the door to closed position, but when this resistance is sufficient to prevent slamming under full power 25 of the closing means, when less power is exerted, as when the closing device is put under partial tension only by a partial opening of the door, the retarding resistance will be so great that it will not be overcome by the 30 power of the closing means and the door will stand ajar, this being particularly true when the door is opened but a short distance and the benefit of inertia is lost.

An object of this invention is to provide 35 an automatic adjustment of the checking or retarding means whereby the resistance offered by such means will be increased with the increase of power of the closing means, and such resistance will be only sufficient to 40 prevent slamming and never so great as to prevent the closing means from fully closing the door, as when the door is opened but a short distance, thus making sufficient power of the closing means available regardless of the degree of opening movement, to 45 insure the complete closing of the door under all conditions.

A further object is to provide a simple 50 construction which may be cheaply manufactured and is particularly adaptable for use upon comparatively light swinging

structures. It is also an object to provide certain other new and useful features in the construction, arrangement and combination of parts, all as hereinafter more fully set forth.

With the above and other ends in view, the invention consists in the matters hereinafter set forth and more particularly pointed out in the appended claims, reference being had 60 to the accompanying drawing in which—

Figure 1 is a perspective view of mechanism illustrative of the invention and showing the same as applied to the upper portion of a door and door casing;

Fig. 2 is a plan view of the same showing the door in partially open position;

Fig. 3 is an enlarged detail showing tension regulating mechanism in elevation;

Fig. 4 is a sectional detail substantially 70 upon the line X—X of Fig. 3;

Fig. 5 is a perspective detail of a friction block, and

Figs. 6 and 7 are a plan view and end elevation respectively of a trip block.

As shown in the drawing, A indicates any ordinary swinging closure, such as a door, window, or the like, which is hung to swing upon a pivotal support, such as the hinge or 80 hinges B connecting one edge of the door to the casing C or other adjacent frame work surrounding the door-way or opening, and as illustrative of suitable power means for closing the door when swung to open position, a coiled spring D is shown as attached 85 at one end to the inner side of the door, and at its opposite end to that side of the door casing upon which the door is hung, so that as the door is swung to open position, this spring will be put under tension and exert 90 a pull to return the door to closed position. Obviously any other suitable power device 95 arranged to be operated by the opening of the door, for exerting a force to automatically swing the door to closed position, may 100 be employed, said spring, as shown, being merely illustrative of one means commonly employed for the purpose.

This invention relates to means for checking or retarding the closing movement of the door just prior to its reaching closed position as it is swung shut by its closing means or spring D, and comprises friction means 105 preferably located adjacent the free edge of the door to come into action just before the door reaches closed position, together with means for adjusting the action of the fric-

tion means according to the variation of the power of the closing means and the resistance required to check the door under the influence of such power, and prevent slamming.

As illustrative of suitable friction means which may be employed for the purpose, a cam block 1 is shown as being secured to the casing C just above the upper edge of the door and adjacent the free edge of the door. This block 1 has a curved side edge 2 which is adapted to be engaged by a friction block 3 carried by a swinging arm 4 pivotally attached at 5 to a plate 6 which is secured in any suitable manner to the face of the door adjacent its free edge and just below the cam block 1, in such a position that the friction block will engage the formed edge 2 and ride against the same as the door swings upon its hinges to closed position. As shown in Fig. 5 this cam block 3 is pivotally supported upon the upper end of the arm 4 by being provided with a hole therein to receive a pin or stud 7 extending from the end of the arm, the block being free to turn upon this stud and resting upon a plate or head 8 secured upon the end of the arm 4. The turning movement of the block 3 is limited in one direction by a stop 9 on the plate 8 and is normally held in engagement with this stop by means of a pin 10 on the plate extending vertically therefrom and having a rounded upper end engaging an inclined surface 11 of a notch in the bottom end of the block.

As the friction block 3 comes into contact with the cam block 1, said friction block is free to turn upon its stud 7 and adjust itself to the curved edge 2 of the cam block, thus presenting a wide friction surface to said edge. By properly positioning the stop 9 the friction block, when out of contact with the cam block, will be held in the proper angular relation relative to its arm 4 to bring its contact side squarely into engagement with the surface 2 of the cam block when the door swings toward closed position but is free to adjust itself to said surface 2 as it moves along in contact therewith, by reason of being free to turn upon its stud 7, said block being lifted bodily as it turns away from the stop 9 by the engagement of the pin 10 with the inclined surface 11 on the block. As soon as the friction block passes out of engagement with the cam block, said friction block will fall by gravity, sliding down upon its stud 7 and at the same time being turned by the engagement of the pin 10 with the surface 11, into engagement with the stop 9.

To firmly hold the friction block 3 in contact with the surface 2 when brought into engagement therewith, and thus provide a frictional resistance to the closing movement of the door, a coiled spring 12 is attached at

one end to the arm 4 carrying the block 3, and by reason of the pivotal attachment of the arm to the door by the pivot 5, said arm will be swung upon its pivot by the spring 12 and be normally held in a position to engage the cam block 1, the arm 4 being limited in its swinging movement by providing a guide 13 upon the plate 6, the ends of which guide form stops to limit the swinging movement of the arm in each direction.

To adjust the tension of the spring 12 so that the friction block 3 will be held with greater or less force in contact with the cam block according to the amount of friction required to prevent slamming, the opposite or rear end of this spring 12 is attached to an adjusting rod 14 which passes through an opening in a stud 15 pivotally attached to a toothed segment 16 mounted upon a plate 17 secured in any suitable manner to the face of the door adjacent the hinged edge thereof and near the upper end of the door. The end of the rod 14 which passes through the opening in the stud 15, is screw-threaded to receive an adjusting nut 18 adapted to engage the side of the stud and adjust the rod longitudinally through the stud to vary the initial tension of the spring 12. The segment 16 is pivotally attached to the plate 17 by the pivot pin 19 and this segment has a laterally and rearwardly extending arm 20 which is formed integral with the segment or secured thereto to turn therewith. A contact block 21 is secured to the door casing C adjacent the plate 17 on the door and in such a position that when the door is swung to open position, the arm 20 will be brought into contact with the block 21 and thus turn the segment 16 upon its pivotal support 19. The position of the arm 20 is such that the segment will be turned in the proper direction to exert a pull upon or automatically set the spring 12 through its connection therewith by means of the stud 15 and rod 14. This automatic setting of the spring 12 or the tension which is thus put upon it, is held or stored up in the spring by providing a pawl 22 on the plate 17 to engage the notches 23 in the edge of the segment 16 and thus lock the segment in the position to which it is turned by the engagement of the arm 20 with the contact member 21.

Pivotal attached to the door casing C directly above the plate 17 on the door, is a gravity block 24 which is hinged or otherwise pivotally attached at its upper edge at 25 to the door casing, and has its lower side cut away as at 26 to permit an arm or hook 27 on the pawl 22 to pass beneath the block as the door swings toward closed position, the upper end of the arm 27 of the pawl 22 engaging the block and lifting it against the force of gravity as the arm passes beneath it. When the door comes to a closed position the arm 27 passes from beneath the end of

the block and when the door is again swung toward open position, this arm is brought by the swinging movement of the door into engagement with a cam plate 28 on the end 5 of the block having a forwardly inclined or cam edge 29 in engagement with which the arm 27 rides as the door swings open, thus forcing the arm away from the end of the gravity block and turning the pawl 22 upon 10 its pivot, thus releasing the pawl from engagement with the toothed segment 16 which is then free to turn and release the tension of the spring 12. The first movement of the door from closed position will 15 therefore relieve the tension of the spring 12 which has been previously set by the full swing of the door to open position, and the frictional contact between the friction block 3 and its cam block 1 will therefore be at 20 once relieved and permit the free opening movement of the door.

This release of the tension of the spring 12 at the very beginning of the opening movement of the door, eliminates the friction 25 which would otherwise be increased by the tension put upon the spring by the previous opening movement of the door which sets the spring, and therefore, if a child, in passing through the door way, should open 30 the door but a short distance, and then release it, the closing spring D would have sufficient force to fully close the door, as in this condition the door will be checked in its 35 closing movement by the friction caused by the initial adjustment of the spring 12 which is effected through the provision of the adjusting nut 18.

Should the door be swung to half open position, or approximately so, the arm 20 40 will be brought into contact with the contact member 21 and the spring 12 will then be put under an increased tension or automatically set thereby, as previously described, but this tension will not be as great 45 as though the door be swung to full open position for the reason that this partial swinging movement will turn the sector 16 only a short distance. However the spring 12 will be put under sufficient tension to 50 check the door and prevent slamming when closed by the tension under which the spring D is placed by this partial opening of the door.

When the door is opened to the fullest 55 extent, the spring D is put under the heaviest tension thereby and exerts its greatest force in closing the door. The door, in swinging from full open to closed position, also has a considerable inertia and therefore it is necessary, in order to prevent slamming, that the 60 spring 12 be put under considerable tension in order to check this heavy force which swings the door closed, and therefore the tension mechanism is so arranged that the 65 swinging of the door to full open position

will turn the sector 16 a considerable distance, putting the spring 12 under a comparatively heavy tension, which tension is held by the locking of the sector 16 by means of the pawl 22. As previously described, 70 this heavy tension of the spring 12 is at once released upon again swinging the door toward open position, by the engagement of the arm 27 with the cam plate on the gravity block 24, which engagement operates to turn 75 the pawl 22 and release the segment 16. The tension of the spring 12 is therefore automatically set in accordance with the degree of opening movement of the door and the resultant tension of the closing spring D. 80 Obviously other checking means which fall within the scope of the appended claims, than those as embodied in the cam block 1 and friction block 3 may be employed, and other mechanism than the pawl and sector 85 with its operating and releasing arms may be employed to adjust the checking means and vary its operation according to the force of the closing means, or spring D, and the degree to which the door is opened. 90 Further, such other changes in the construction and arrangement of parts as fall within the scope of the appended claims may be made without departing from the spirit of this invention and I do not therefore limit 95 myself to the particular mechanism shown.

Having thus fully described my invention, what I claim is:—

1. In a device of the character described, the combination of means for retarding the closing movement of a closure, including a spring, and means for automatically varying the tension of said spring to vary the retarding effect of said retarding means in proportion to the opening movement of the closure. 100

2. In a device of the character described, the combination of means for checking or retarding the closing movement of a closure including a spring, and means for varying the tension of the spring, operated by the opening movement of the closure. 110

3. In a device of the character described, the combination of means for checking the closing movement of a closure including a spring, means operated by the opening movement of the closure for varying the tension of said spring, and means for automatically releasing the tension of said spring. 115

4. In a device of the character described, the combination of means for frictionally retarding the closing movement of a closure, and means automatically operated by the swinging of the closure toward open position for increasing the frictional resistance of said retarding means. 125

5. A device as characterized in claim 4, and including means operated by a limited movement of the closure for releasing the 130

increased frictional resistance of the retarding means.

6. In a device of the character described, the combination of a cam member adapted to be secured to a closure casing adjacent the free edge of the closure, a friction member carried by the closure, and means for yieldingly holding the friction member in position to frictionally engage the cam member.

7. A device as characterized in claim 6, and wherein the friction member is rotatively supported upon a pivoted arm to swing toward and from the cam member.

8. A device as characterized in claim 6, and including means carried by the door adjacent its hinged edge and operated by an opening movement of the door for putting the yielding means under tension.

9. In a device of the character described, the combination of means for checking the closing movement of a door and including a spring, a pivoted member adapted to be turned by an opening movement of the door and to which said spring is connected to be put under tension by such turning movement, means for holding said pivoted member in the position to which it is turned, and means for releasing said member.

10. In a device of the character described,

the combination of a cam member adapted to be secured to a door casing adjacent the free edge of the door, a friction member carried by the door to engage the cam member upon the swinging of the door to a closed position, a spring to yieldingly hold the friction member in position to engage the cam member, a toothed segment pivotally attached to the door adjacent the hinged edge thereof, means for connecting one end of the spring to said toothed member, an arm on the toothed member, means on the door casing for engaging the arm when the door is swung towards open position to rotate the toothed member and place the spring under tension, a pawl for engaging the toothed member and holding the same in the position to which it is turned, and means for releasing the pawl.

11. A device as characterized in claim 10, and wherein the pawl releasing means includes a gravity member attached to the casing adjacent the pawl and provided with a cam plate to operate the pawl.

In testimony whereof I affix my signature in presence of two witnesses.

EARL C. AKERS.
